**SMOKE HOOD FOR ELECTRIC FURNACES
AND THE LIKE**

Enrico Erni, Muhlacker, Gerlafingen, Switzerland, assignor to Gesellschaft der Ludw. von Roll'schen Eisenwerke A.G., Gerlafingen, Switzerland, a corporation of Switzerland

Filed Oct. 3, 1960, Ser. No. 60,017

Claims priority, application Switzerland Oct. 6, 1959
3 Claims. (Cl. 13—15)

The present invention relates generally to a protective covering or smoke shield for furnaces and, more particularly to a smoke hood particularly suitable for use in conjunction with open electrical furnaces.

It is well known that open electric furnaces employed for various metallurgical purposes generate substantial quantities of smoke during their operation which are both a nuisance and danger for the operators as well as for the surrounding community. Such generation of smoke and stack gases naturally does not occur in closed furnaces. However, since open electric furnaces are oftentimes employed in a wide variety of applications for practical reasons the problem of safely handling and exhausting the smoke is continually present when employing such furnaces. Up to the present it was common practice to permit the stack and smoke gases produced by these open electric furnaces to freely flow into the workshop from where they were removed by means of flues.

In accordance with the teachings of the present invention it is proposed to provide a novel smoke hood for effectively collecting the smoke and stack gases emerging from the furnace and operating independently of and without contact with the furnace charge while still safely ensuring protection of the working area around the furnace. In thus carrying out its required function, the smoke hood should also be designed to facilitate physical access to the furnace interior and permit visual observation thereof in a reliable and dependable manner under all operating conditions without unduly increasing the cost of its manufacture and installation. Accordingly, there is provided a smoke hood having a housing member consisting of a plurality of telescopically arranged wall portions adapted to be displaced relative to one another, said wall portions being arranged circumjacent an electrode holder member adapted to carry the electrode. The smoke hood is provided with insulating means suitably electrically insulating the electrode holder member from the slidably and telescopically arranged housing. The smoke hood may also be provided with one or more flues for directing the gases to a desired location. Additionally, it has been found advantageous to provide inspection windows on the housing member and also to provide the wall portions thereof with cooling compartments to prevent undue heating of the smoke hood by the effluent gases and smoke. The advantages of a smoke hood constructed in accordance with the teachings of the present invention resides in the fact that it can be installed on existing furnaces without great difficulty; it ensures protection against the smoke and gas emanating from the furnace even when the volume thereof is substantial; it readily permits visual inspection of the furnace interior; and the smoke hood can at all times be partially or fully raised for charging, checking, cleaning or any other desired operation so as to render accessible the furnace interior and the electrode.

Accordingly it is an important object of the present invention to provide means for removing gases emanating from a furnace in a safe and reliable manner.

It is a further object of the present invention to provide a novelly constructed smoke hood for open electric furnaces and the like which is relatively simple to manu-

2

facture and can be easily installed on existing structures without undue difficulty or high installation costs.

It is another object of the present invention to provide means for conveying away undesirable waste gases from a furnace while permitting relatively easy physical and visual access to the furnace interior.

Yet another object of the present invention is the provision of a smoke hood for electric furnaces which can be easily accommodated thereon, is relatively simple in construction but highly efficient in operation, and is safe during its operation.

These and still further objects of the present invention and its entire scope and applicability will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

In the drawings:

FIGURE 1 is a vertical sectional view of the upper portion of an open electric furnace employing electrode means and provided with a smoke hood constructed in accordance with the teachings of the present invention;

FIGURE 2 is a plan view of the device shown in FIGURE 1;

FIGURE 3 is an enlarged view of a wall portion of the smoke hood shown in FIGURE 1 and provided with a viewing window; and

FIGURE 4 is an enlarged view of a wall portion of the smoke hood shown in FIGURE 1 provided with cooling compartments.

Referring now to the drawings and, more particularly, to FIGURES 1 and 2 thereof, a smoke hood A is provided with an upper stationary annular wall member 1 supporting on its upper surface 1a one or more flues 2 communicating with the furnace interior via the apertures 2a. Disposed below the upper wall member 1 are the further wall members 3 and 4 which are arranged for sliding telescopic movement with respect to one another. Each of the wall members are provided with the laterally projecting annular ribs 1b serving to slidably interconnect adjacent wall members to permit said telescopic movement in order to expose the interior of a furnace 6 and its electrode 5 mounted in an electrode holder 7 circumjacent to which the smoke hood A is arranged. The left-hand portion of FIGURE 1 shows the housing of the smoke hood A consisting of the relatively movable wall members 1, 3 and 4 in raised position to permit access to the furnace interior, whereas the right-hand portion of FIGURE 1 shows the housing lowered almost to the extent of the upper surface 6a of the furnace. It is, of course, to be understood that any number of individual wall members may be employed depending upon the desired height of the smoke hood and the physical dimensions of the furnace to which it is applied.

Intermediate the flues 2 and the centrally arranged electrode holder 7 there is provided on the upper surface 1a of the upper wall member 1 an insulating ring 8 formed of an electrically non-conductive, mechanically and thermally stable material, as for example, asbestos, or a ceramic material or the like. This insulating ring 8 performs a dual function, to wit: it must on the one hand electrically insulate the current-carrying electrode holder 7 from the smoke hood A to safeguard against passage of current to the smoke hood A and the furnace 6; whereas, on the other hand, it must permit a relative movement of the electrode holder 7 with respect to the wall member 1 of said smoke hood in the direction of the double headed arrow B—B to allow for a change

of position of the electrode 5 without allowing considerable quantities of smoke or waste gases escaping at this point into the working area.

If the mechanical and thermal stresses applied to the insulation ring 8 are sufficiently low, this ring 8 may also be formed of a synthetic material such as a phenol formaldehyde condensate. The insulating ring 8 may naturally be dispensed with entirely and be replaced by a non-conductive layer, by way of example formed of mica, or a sufficiently thermally stable insulating coating formed on an organic or inorganic basis. Although the provision of suitable insulation means is not particularly important for the smoke hood A insofar as its ability to remove smoke and waste gases is concerned, it is, however, quite essential for practical reasons since completion of a circuit between the smoke hood A and the electrode 5 must be absolutely prevented in view of the danger of accidents and damage to the smoke hood itself. The particular smoke flues 2 employed must be suitably dimensioned in accordance with the prevailing conditions of operation. The arrangement and operation of the apparatus and, in particular, the number of flues employed must be adapted to the volume of smoke desired to be removed. Any known or conventional fluid conveying means such as fans, blowers, steam ejectors or the like may be employed to aid in the exhaustion of the waste gases from the furnace.

In the embodiment shown in FIGURES 1 and 2, the electric furnace 6 is provided with a circular cross-section and one electrode 5 is employed. It is, of course, to be understood that furnaces having other cross-sectional configurations and employing a plurality of electrodes may be equipped with the smoke hood A designed according to the teachings of the present invention. Thus, for example, the smoke hood A may obturate furnaces having rectangular, hexagonal, polygonal or oval cross-sections and using several electrodes. The hood must then naturally be designed with a correspondingly shaped cross-section so that it will cover the entire furnace interior and encloses the corresponding number of electrodes, in a manner illustrated in FIGURE 2. The smoke hood A is preferably formed of sheet iron or steel. But other metals, such as aluminum, may also be advantageously employed while keeping under consideration the thermal stability of the material to be employed.

The telescopically displaceable members 3 and 4 are preferably designed as shown in detail in FIGURE 3 and are provided with the laterally extending rib portions or flanges 1b engaging adjacent flanges of the adjacently arranged wall portions to permit such sliding and telescopic movement as already detailed hereinabove. The rib portions 1b not only serve to interconnect the respective wall portions 1, 3 and 4 of the smoke hood A but define limit stops for determining the extent of movement of said wall portions in their fully raised and lowered positions. In order to facilitate inspection of the furnace interior, at least some of the wall members may be provided with windows 12 as clearly shown in FIGURE 3 in order to cover a suitably provided opening 12a provided on an associated wall member 9. The window 12 may be formed of any suitable transparent sheet of material, as for example, mica, temperature resistant glass formed with or without reinforced wiring, or a metal fabric. In this connection, the operating temperatures of the furnace and its cooling conditions must be taken into consideration.

It is also sometimes desirable to provide a cooling system for the smoke hood A. In FIGURE 4 there is illustrated an enlarged, fragmentary, cross-sectional view of an individual wall member 10 internally provided with cooling compartments 11 through which circulates a suitable cooling medium, such as water, received from a source S via the flexible supply conduit 12' communicat-

ing with the rib portion 1b and returned to said source via the flexible return conduit 14. Other possible cooling system depending on the conditions of operation of the smoke hood may be provided. If a water cooling system is provided which washes the entire outer surface of the telescopically displaceable members of the hood housing, care must be taken to ensure that the cooling medium does not enter the interior of the smoke hood. It is, of course, possible to carry out raising and lowering movement of the displaceable wall members by means of mechanical means actuated by any conventional motor, or to provide a pulley system to gain a mechanical advantage in order to move the wall members relative to one another. Similarly, such raising and lowering movement can be carried out by any conventional pneumatic or hydraulic device.

I claim:

1. The combination with an open electric furnace having an electrode holder and an electrode member mounted in said holder, of a smoke hood mounted over and normally closing the open end of said electric furnace which comprises a housing member arranged circumjacent said electrode holder, said housing member including separate adjacently arranged slidable wall members mounted for telescopic movement, said wall members being provided with means supportably interconnecting said adjacent wall members for sliding telescopic movement to permit raising and lowering of said wall members to expose and obturate the interior of said open electric furnace.

2. The combination with an open electric furnace having an electrode holder and an electrode member mounted in said holder, of a smoke hood mounted over and normally closing the open end of said electric furnace which comprises a housing member provided with a plurality of separate slidably arranged wall members disposed adjacent one another, said separate wall members each being provided with rib portions engageable with the rib portions of an adjacently disposed wall member permitting sliding and telescopic movement of said housing member into a retracted and extended position, at least one of said wall members being provided with window means for exposing the interior of the furnace when said housing member is in said extended position.

3. The combination with an open electric furnace having an electrode holder and an electrode member mounted in said holder, of a smoke hood mounted over and normally closing the open end of said electric furnace which comprises a housing member provided with a plurality of separate slidably arranged wall members disposed adjacent one another, said separate wall members each being provided with rib portions engageable with the rib portions of an adjacently disposed wall member enabling sliding and telescopic movement thereof and defining a limit stop for movement of said wall members, flue means carried by said housing member in registry with the interior of said electric furnace to remove gases therefrom, and insulating means cooperable with said housing member to insulate the same against leakage of current from the electrode through said housing member.
